ROLLER LATCH

David M. Robinson, New Britain, Conn., assignor
to The Stanley Works, New Britain, Conn., a
corporation of Connecticut

Application May 14, 1948, Serial No. 27,026

5 Claims. (Cl. 292—75)

1

The present invention relates generally to latches and, more particularly, to roller latches of the type comprising a spring loaded roller supported in the edge of a door for engaging a strike or keeper mortised into the jamb.

Roller latches of the type referred to are commonly utilized on interior doors which do not require a positive latch. Such latches are effective to retain the door in closed position by reason of the resistance to compression of the roller supporting spring but at the same time the door may be readily opened merely by applying sufficient opening force which causes the roller to ride up on the strike and thus release the latch.

When a roller latch is installed in a door, it will be appreciated, the functioning of the roller latch will depend on the amount of compression to which the supporting spring is subjected when the door is opened and closed. The desired amount of resistance to be obtained by the spring will vary in accordance with the intended use of the door and the wishes of the user. The amount of compression obtained will vary unless adjusted as a result of varying distances between the door and jamb, this being different not only as between different installations but will also vary in the same door with the seasons as the door expands or contracts due to moisture conditions.

Accordingly, it is an object of the invention to provide a roller latch which has an adjustable spring action such that the amount of compression of the spring when the door is opened and closed may be adjusted as desired.

A principal object of the invention is to provide such an adjustable feature whereby the spring compression may be adjusted without removing the latch from the door thus facilitating the adjustment of the spring to the desired degree for the particular installation and without need for disassembly of the latch.

Another principal object of the invention is to provide such an adjustable arrangement which not only is operable while the latch is mounted in the door and without disassembly of the latch but which has the added feature of being adjustable without the use of any tools whatsoever, the construction being such that the latch members may be manually unlocked, manipulated and relocked in adjusted position with a minimum expenditure of time and effort and without the use of any instrumentality other than the fingers of the operator.

A further object of the invention is to provide such an adjustable latch which is foolproof in

2

operation, which is made of a minimum of parts, which is easy and economical to fabricate and assemble, and which is of simple and rugged construction such that it will provide long and satisfactory service without the need for frequent replacements and repairs.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the drawings—

Figure 1 is a plan view of the latch mounted in a door with the door, jamb and strike being shown in cross section;

Fig. 2 is a view similar to that in Fig. 1 except that it is taken at 90° therefrom and with the latch housing in cross section to show the internal parts of the latch;

Fig. 3 is an end view of the latch;

Fig. 4 is a cross sectional view taken along the line 4—4 of Fig. 5; and

Fig. 5 is a sectional view of the latch positioned as viewed in Fig. 1.

Referring to the drawings, the latch A, embodying the present invention, is shown mounted in the edge of a door B where it will engage a keeper C which is mortised into a jamb D in the usual manner. The latch of the present invention is intended to be used like any other roller latch where it is not required to have a positive latch, such as on closet doors or any other interior residential door, for example. The latch will provide a sufficient holding force to handle a full size residential door. The latch may be of any desired size but in the preferred embodiment is sufficiently small so as to fit into a hole in the edge of the door of the order of $\frac{1}{8}$ inches in diameter.

The latch includes a cylindrical or tubular housing 10 which is adapted to fit into the hole 11 in the edge of the door B as above described. The housing 10 is provided at its outer end with a plate 12 which may be secured to the edge of the door B by any suitable means such as the screws 13. A face plate 14 conforming in outline to the plate 12 may be provided to improve the appearance of the assembled latch.

The housing 10 has a reduced portion 15 which is internally threaded as at 16 so as to threadably receive a bushing 17 which is similarly threaded. By turning the bushing 17, it will be

apparent that the bushing may be adjusted toward and away from the edge of the door.

The bushing 17 has a central opening 18 which, in the specific embodiment shown, is of square cross section so as to correspond to the cross section of a plunger 19. The plunger 19 is provided at its outer end with a yoke 20 which is considered part of the plunger and is adapted to fit within the housing 10, this yoke being provided with a transverse shaft 21 on which is rotatably mounted a conventional hard rubber roller 22.

A spiral spring 25 is loosely mounted on the plunger 19 between the yoke 20 and the bushing 17. This spring 25 resiliently opposes any inward thrust of the plunger 19 and hence retraction of the roller 22. The inner end of the plunger 19 has a small washer 26 fixed thereto to provide a flange and between this washer 26 and the bushing 17 there is provided a second spiral spring 27 which is also loosely carried on the plunger 19. The spring 27 is considerably lighter than the spring 25 and merely serves to yieldingly retain the plunger 19 in the retracted position with the yoke 20 abutting against the spring 25.

The housing 10 is provided with a series of longitudinal indentations or grooves 30 of which two grooves 30a are somewhat wider and deeper than the remaining grooves. The yoke 20 is provided at opposite sides with a pair of notches 31a which are of sufficient depth to receive the grooves 30 and thus permit the yoke to enter the housing 10 and, when the yoke is so received into the housing, prevent the yoke from turning. The latch grooves 30a are at opposite sides of the door so that, when the yoke is received into the housing 10, the roller will always be at right angles to the path of movement of the door and therefore will be properly positioned for proper functioning. The remaining grooves 30 are received in corresponding notches 31 in the yoke 20 which further assists in positioning the yoke.

During closing movement of the door B, the roller 22 is first cammed inwardly by the strike portion 32 and then, when the door is fully closed, the roller is moved outwardly by the expansion of spring 25 to the fullest extent permitted by the recessed portion of the keeper C, thereby retaining the door in closed position. The adjustment of the latch is preferably such that the spring 25 is not fully extended when the door is closed and the degree to which it remains compressed, of course, depends upon the adjusted position of bushing 17. When sufficient opening force is applied to the door, the roller 22 will be again cammed inwardly by the strike portion 32 permitting the roller to clear the jamb. However, because of the shape of the strike portion 32, the resistance to opening movement of the door is about four times that which is exerted during closing movement of the door. It will be apparent, therefore, that the amount of force exerted by the spring 25, both when the door is fully closed and during opening and closing movements, will depend upon the design of the keeper C, which would be the same in most installations, and the extent to which spring 25 is compressed which, in turn, depends upon the adjusted position of the bushing 17 as aforesaid.

It is an important advantage of the present invention that the latch formed as described herein may be readily adjusted without disassembly of the latch and without the use of any tools whatsoever. In order to adjust the posi-

tion of the bushing 17, it is only necessary for the operator merely to grasp the roller 22 between the thumb and forefinger and pull out the plunger 19 to a sufficient amount such that the yoke 20 will clear the housing 10. It is then a simple matter to turn the yoke 20 and hence the plunger 19 which, in turn, rotates the bushing 17 to move it in or out in the reduced portion 15 of the housing 10. Turning of the bushing 17 when the plunger 19 is turned is caused by the square cross section of the plunger 19 and the opening 18 in the bushing 17 which permits sliding movement between the plunger 19 and the bushing 17 but does not permit relative turning of one with respect to the other. Washer 26 prevents the plunger 19 from being entirely withdrawn.

When the plunger 19 has been turned sufficiently to adjust the bushing 17, the roller 22 is properly aligned, that is, turned parallel to the floor and then released whereupon the spring 27 will retract the plunger 19 and yoke 20 into the housing. With the roller 22 so aligned, the notches 31a will receive the grooves 30a and thus permit the yoke to enter into the housing and thereafter prevent the yoke and plunger from turning.

When the foregoing adjustment has been accomplished, the door may be tested by opening and closing same to see if the latch is properly adjusted. If further adjustment is required, the operation above described may be readily repeated until the proper adjustment is accomplished. Inasmuch as it is unnecessary to disassemble the latch or to utilize any tools, it will be apparent that an exact adjustment will be accomplished in a minimum of time and with a minimum of effort.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A roller latch comprising a housing adapted to be mounted in the edge of a door, a supporting member threadably received in the housing and adapted by turning to be adjusted toward and away from the edge of the door, a plunger in said housing slidably but non-rotatably received through said member, a roller supported on the outer end of the plunger, and spring means supported by said member for urging the plunger outwardly.

2. A roller latch comprising a housing adapted to be mounted in the edge of a door, a supporting member threadably received in the housing and adapted by turning to be adjusted toward and away from the edge of the door, a plunger in said housing longitudinally slidably but non-rotatably received through said member, spring means extending between the member and the plunger for yieldingly supporting the plunger in predetermined longitudinal position, and roller supporting means on the outer end of the plunger adapted by engagement with the housing when

the plunger is in said predetermined longitudinal position to prevent the plunger from turning.

3. A roller latch comprising a housing adapted to be mounted in the edge of a door, a supporting member threadably received in the housing and adapted by turning to be adjusted toward and away from the edge of the door, a plunger of non-circular cross section extending through said member, said member having an opening corresponding to said cross section for slidably and non-rotatably receiving the plunger and said plunger including a roller support fixed to the outer end thereof, a roller carried by said support, means for yieldingly maintaining the plunger in predetermined longitudinal position with respect to the supporting member such that the roller extends outwardly from the housing including a first spring extending between the roller support and the adjacent side of the supporting member, a second spring at the opposite side of the supporting member, and means on the inner end of the plunger for engaging the second spring, and interengaging means on the housing and roller support for preventing turning of the support while the plunger is in said predetermined position, said roller being adapted to be manually drawn outwardly to free the roller support from the housing to permit the plunger to be turned to adjust the said supporting member.

4. A roller latch comprising a housing adapted to be mounted in the edge of a door, a supporting member threadably received in the housing and adapted by turning to be adjusted toward and away from the edge of the door, a plunger of non-circular cross section extending through said member, said member having an opening corresponding to said cross section for slidably and non-rotatably receiving the plunger, a roller support fixed to the outer end of the plunger, a roller carried thereby, a flange on the inner end of the plunger, a first spring extending between the roller support and said member for resiliently resisting inward movement of the plunger, a second spring extending between the flange and said member for resiliently resisting outward movement of said plunger, and interengaging means on the housing and roller support to prevent rotation of the support within the housing and to

prevent entry of the support into the housing except when the roller is in predetermined angular relationship with respect to the housing.

5. A roller latch comprising a generally cylindrical housing adapted to be mounted in the edge of a door, a supporting member threadably received in the housing and adapted by turning to be adjusted toward and away from the edge of the door, a plunger of polygonal cross section extending through said member, said member having an opening corresponding to the cross section of said plunger for slidably but non-rotatably receiving the plunger, a roller support on the outer end of the plunger, a roller carried thereby, said support and the housing being provided with indentations and ribs, respectively, such that the member may be slidably and non-rotatably received into the housing only when the roller is in a predetermined angular position with respect to the housing, a helical spring on the plunger extending between the roller support and said member for yieldingly resisting inward movement of the plunger, a flange on the inner end of the plunger, and a second helical spring on the plunger extending between said flange and said member for yieldingly resisting outward movement of the plunger whereby the roller support may be manually pulled outwardly to clear the housing and to turn the plunger to adjust the supporting member following which the roller support may be released for reentry into the housing when the roller is in said predetermined angular position.
